UNITED STATES PATENT OFFICE.

WILLIAM HEAD COLEMAN, OF NEW YORK, N. Y.

APPARATUS FOR HEATING AIR, STEAM, &c.

SPECIFICATION forming part of Letters Patent No. 393,540, dated November 27, 1888.

Application filed October 6, 1886. Renewed February 29, 1888. Serial No. 265,680. (No model.)

To all whom it may concern:

Be it known that I, WILLIAM HEAD COLEMAN, a citizen of the United States, and a resident of the city, county, and State of New York, 5 have invented certain new and useful Improvements in Apparatus for Heating Air, Steam, or Equivalent Medium, of which the following is a specification, reference being had to the accompanying drawings.

10 The object of such invention is to devise an improved apparatus whereby the heating and distributing of air, steam, or equivalent medium may be thoroughly and economically accomplished and the resultant temperature of 15 the heated medium kept well under control.

The apparatus may be used for heating or reheating air or for heating or superheating steam or gases or any equivalent medium capable of being passed through the retorts. A 20 special use to which it may be applied is the furnishing of heated dry air or moist air for seasoning lumber or for drying malt, grain, or like products and materials.

25 My improvements consist in the combination of the several portions collectively or with each other, as may hereinafter be described and claimed.

In the drawings, Figure 1 represents a sectional elevation of a furnace provided with 30 my improved retorts. Fig. 2 represents a sectional elevation of furnace, flue, or connection with retorts in place. Fig. 3 represents a longitudinal section and front elevation of the retorts. Fig. 4 shows details of saturator or 35 sprinkler for moistening or impregnating the passing medium with additional improving material. Fig. 5 represents front elevation of furnace or chamber with wall-plates in position to hold the retorts. Figs. 6, 7, and 11 show the 40 method of connecting the retorts with supporting-plates. Fig. 6 shows an outside view of retort-leg A, with supporting-plates C, in section. Fig. 7 is a vertical section through inclosing-walls D and a side view of both legs of the 45 retort and supporting-plates C, the upper portion being broken away. Fig. 7 also shows the gate-valves G, G', and I and connections H in place. Fig. 11 shows a horizontal section through walls of furnace or chamber. It 50 also shows a plan and side view of valves G, G', and I. Valves G, G', and I are constructed

alike, being for air purposes, as shown. When steam or gas is to be passed through the retorts, a tight gate valve or screw-stop valve will necessarily be used. Fig. 8 represents a 55 front view of the supporting-plates in halves at x x, with the upper retort-leg in section and lower retort-leg flanged. Fig. 9 is a rear view of the supporting-plates with section through retort-legs at y y, and showing flanges or lugs 60 c' in position. These lugs c' may be carried about the legs A to a full circle, but are preferably made as shown. Fig. 10 shows special detail of plates C separated.

Similar letters of reference designate like 65 parts in all the figures.

A A designate the legs of the retort, and A' the return-bend connecting the same. These retorts are arranged singly or in sets, to be heated by direct heat-radiation or by the passage of products of combustion from a furnace or heat-generating apparatus more or less distant from the retorts. 70

B designates a furnace immediately below the retorts. 75

C designates the divided supporting-plate, each portion of which is made to fit into a neck or groove formed between front flanges, c c, and inner lugs, c' c', on both legs of retort. The halves of the supporting-plate, as represented, are brought into close-joint contact and bolted securely to the walls of the furnace or heating-chamber at bolt-holes a a, &c. The rear or return portion, A', is supported at c' upon a cross-bar extending between the 80 walls of the chamber. Spiral partitions, &c., or diaphragms are placed within the legs A A of the retorts to form channels for the air to pass through and present a maximum of heat contact. 85

In the upper leg A of the retort, as shown in Fig. 3, a single spiral is shown. In the lower leg A a double spiral is shown, forming the channels c' c'. At the bends of the retorts coils of wire c' are placed to fill up the return 95 space, as well as act as a retarding and convection material. Chips of metal and like material may be used.

On the outer surface of the retorts ribs c' are placed or cast to present increased external heat-absorbing surfaces. 100

At c' a lug or projection is formed to rest

upon a supporting-bar, *m*, attached to and extending between the inclosing walls or sidings of the furnace or heating-chamber.

D designates the inclosing walls or sidings

5 forming the heating furnace or chamber. They are constructed of brick or stone for stationary purposes and lined with fire-brick or heat-resisting materials. The walls or sidings may be of metal, with similar heat-resisting lining 10 for portable uses.

E designates a moistener or saturator. In the detail, Fig. 4, a perforated sprinkler-coil is placed either double, as in the cross-section, or single, as in the longitudinal section, as 15 shown at *e'* and *e''*. The chamber *E* is enlarged to suit the outer diameters of the flanges of piping or retorts, and the sprinkler-coils set of such sweep and diameter as not to interfere with the area of the piping or passage. The 20 saturating or impregnating medium is admitted under pressure through the pipe-connections *e'*, in quantities to suit requirements, and sprinkled through holes or perforations in the coils *e'* or *e''*.

25 To improve the effectiveness of the furnace or heat-developing apparatus, a blower-pipe, *F*, forms a connection between the retorts and the furnace or between the crosses and furnace, and a jet of air of greater or less magnitude is 30 forced to increase combustion. The valve *f* controls the strength of the jet.

In the construction and operation of the apparatus one or more retorts are projected horizontally into the heating chamber or flue, and 35 each leg *A* of the retort is furnished at its immediate end with a valve, *G*, and cross connection *H*. The cross-connections are joined by a third valve, *I*, and communicating pipes *K* are attached to the upper cross *H*, while 40 discharge-pipes *K'* are attached to the lower cross *H*, or vice versa, according as the movement in the retorts takes place. As represented in the drawings, the air, steam, or heated medium is admitted through *K*, *H*, 45 and valve *G*, passes through the retort, comes in contact with the heated surfaces of the legs and elbows, takes up the heat, and exits through the lower valve, *G*, whence it is conveyed to the required localities. In case the 50 heated medium becomes of too high a temperature, the valve *I* is opened, admitting the unheated material or fluid to mingle with the heated, thus tempering it to the required degree. With a hot fire and a call for low 55 temperature the valve *G* is partially closed and valve *I* opened, or the valve *G'* may be kept full open and valve *G* closed, partially permitting but a limited amount to pass for heating. By varying this manipulation a close 60 accuracy of temperature may be easily attained. The valves *G*, *G'*, and *I* are alike in construction, being here represented as damper or slide-gate valves of ordinary pattern. They may, however, be replaced by valves of any 65 style or type, as necessity or choice may demand. A thermometer may be placed at *h* to indicate delivery temperature. In case the

heated air be too dry for required purposes, moisture of any kind may be sprayed through the saturating-pipes *e'* *e''* in the chamber *E* till 7c the required dampness is attained.

Where direct heat from a furnace is applied to the retorts, a protecting guard-plate, *L*, is curved beneath the lower leg of the retort, protecting it from fracture or damage. The heat 75 passes up through the side spaces, *l l*. An arch, *M*, of fire-brick or similar material, is carried across the space between the legs of the retorts, and this, in combination with the guard-plate *L*, forms a flue along which the 80 heat passes, impinging upon the lower leg of the retort, and, passing up at the elbow, returns along the upper leg to the chimney or uptake, thus effecting the maximum heat exposure and contact.

85 What I claim as new, and desire to secure by Letters Patent, is—

1. In an apparatus for heating air, steam, or equivalent medium, the combination of the herein-described retort, consisting of two legs 90 and a return-bend, each leg being provided with flanges *c* and lugs *c'*, a divided supporting-plate, *C*, fitting into the neck formed between said flanges and lugs and the walls of a heating furnace or chamber, substantially as 95 set forth.

2. In an apparatus for heating air, steam, or equivalent medium, the combination of the herein-described retort, the guard-plate *L*, the dividing-arch *M*, and a heating furnace or 100 chamber, substantially as and for the purposes specified.

3. In an apparatus for heating air, steam, or equivalent medium, the combination of the herein-described retort, consisting of two legs 105 and a return bend, each leg being provided with flanges *c* and lugs *c'*, and the return-bend with lug *c''*, a divided supporting-plate, *C*, walls *D*, and supporting-bar *m*, substantially as set forth.

4. In an apparatus for heating air, steam, or equivalent medium, the combination of the herein-described retort, means for supporting the same in a heating furnace or chamber, dividing-arch *M*, guard-plate *L*, and the inner 115 spiral partitions, *c''*, and coils *c'*, substantially as and for the purposes set forth.

5. In an apparatus for heating air, steam, or equivalent medium, the combination of the herein-described retort, valves *G*, *G'*, and *I*, and 120 intermediate connections, *H* *H*, whereby the temperature of the heated medium is kept under control, substantially as set forth.

6. In an apparatus for heating air, steam, or equivalent medium, the combination of the 125 herein-described retort, valves *G*, *G'*, and *I*, intermediate connections, *H* *H*, pipes *K* and *K'*, and saturator or moistener *E*, substantially as and for the purposes specified.

WILLIAM HEAD COLEMAN.
